UNITED STATES PATENT OFFICE

JOHN H. DOMKEE, OF WEST HAVEN, CONNECTICUT, ASSIGNOR TO THE WIRE NOVELTY MANUFACTURING CO., OF NEW HAVEN, CONNECTICUT, A CORPORATION OF CONNECTICUT

BUTTON LOOP

Application filed February 25, 1929. Serial No. 342,395.

The invention relates to improvement in button loops particularly adapted for use on garment straps, the loop being specially adapted to be suspended at the end of a strap in readiness to be clipped over a button the shank of which may be urged therefrom into a smaller retaining loop from which it cannot be unintentionally withdrawn, and the objects of the invention are to provide from a single piece of wire integral suspension, receiving, and retaining, loop portions of a button loop; and to provide means for securing the wire ends against relative separation out of the general plane of the loops, but permitting them a limited relative movement along such plane. With these and other objects in view as may become apparent from the within disclosures, the invention consists not only of the particular form herein pointed out and illustrated in the drawing but readily admits of certain modifications within the scope of what hereinafter may be claimed.

The following is the description of an embodiment of the invention, reference being had to the accompanying drawing in which the Figure 1 is a face view of the button loop; the Figure 2 is a bottom view thereof; and the Figure 3 is a fragmentary side elevation, partly in cross-section on the dotted lines "3-3" of the Figure 1, but illustrating a slight modification.

Referring more particularly to the drawing in which similar numbers refer to similar parts, the invention is an improvement upon the single piece wire button loop for which an application for Letters Patent, filed February fifteenth, 1929, and Serial Number 340,246, was made, the applicant there disclosing a bifurcation of one of the wire ends adapted to receive the other end to permit a relative movement of the two ends along the plane of the loops. Having provided for the suspension loop 1, made by forming the middle portion of the single piece of wire, and having provided for the two remaining portions to form between them the button receiving loop 2 having the contracted throat 3 and the button retaining loop 4, as in the previously filed application, the im-

provement for which this application is filed introduces a different and novel means by which the overlapping portions 5 and 6 are provided with a limited relative movement along the plane of the loop. These overlapping portions 5 and 6 are laterally flattened to permit the two end portions to lie together substantially within the same general plane as that of the loop. The process of flattening these end portions, by means of applying a heavy pressure thereon, materially increases the width throughout the overlapped portions, as illustrated by the Figure 1. The flattened end portion 6 is provided with the longitudinally extending slot 7, and the flattened end portion 5 is provided with an integrally struck up pin 8 adapted to ride within the slot 7, as illustrated by the Figure 3, the free extremity of the pin 8 extending beyond the slot 7 and being there upset, as illustrated by the Figures 1, 2, and 3, a rearwardly facing shoulder 9 of the upset extremity or head 10 being adapted to engage against the inset surface 11 of a depression 12 in the face of the overlapping flattened end portion 6, as illustrated by the Figures 1 and 3, that the head 10 may ride flush with the exterior surface of the face of the loop 4 to maintain the overlapped portions 5 and 6 in close relation for a limited relative movement only in the plane of the loop as the shank of a button (not illustrated) is urged past the throat 3 to engage within one or the other of the loops 2 and 4. The depression 12 may extend across the flattened end portion 6, as illustrated by the Figure 1, or it may be made to closely surround the slot 7 to leave ribs 12A bordering its longer sides, as illustrated by the Figure 3, the side ribs having a tendency to maintain certain strength to the flattened end portion 6.

What I claim is:

1. A wire button loop comprising a single piece of resilient wire bent to form associated loops, the free ends of the wire being flattened and overlapped to substantially lie together within the plane of the loops, the overlapped ends having a pin and slot connection to permit their relative freedom of movement

in opposite directions along the plane of the loop.

2. A wire button loop comprising a single piece of resilient wire bent to form associated loops, the free ends of the wire being flattened and overlapped to substantially lie together within the plane of the loops, the overlapped ends having a pin and slot connection, the end of the pin being upset to provide a head, the connection permitting a relative movement, of the overlapped ends, only along the plane of the loops.

3. A wire button loop comprising a single piece of resilient wire bent to form associated loops, the free ends of the wire being flattened and overlapped and provided with a pin and slot connection, the surface of the slotted flattened end being provided with a depression around the slot within which depression the end of the pin carried by the other flattened end is upset to provide a head lying flush with the said surface, the connection permitting a relative movement of the overlapped ends, only along the plane of the loops.

4. A button loop formed from a single piece of resilient wire of which the middle portion is bent to form a button receiving loop having a contracted throat communicating with a button retaining loop formed by curved, overlapping, and flattened arm portions, one of the lapped portions being provided with a depressed portion and a longitudinally extending slot within the depressed portion, and the other lapped portion carrying a pin adapted for a sliding engagement within the slot, the pin extremity extending beyond the slot and being there upset to provide a head adapted to ride flush within the depression, the curved overlapping arm portions being thereby secured together for a limited relative movement only along the plane of the loop.

5. A button loop comprising a single piece of resilient wire bent to form associated loops, the free ends of the wire being flattened and overlapped and provided with a pin and slot connection, the surface of the slotted flattened end having an elongated depression surrounding the slot and providing the longer sides of the slot with ribs between which the end of the pin, carried by the other flattened end, is upset to provide a head lying flush with the said surface for protected travel within the depression as the pin travels in the slot.

6. A wire device comprising a single piece of resilient wire bent to form associated loops, the free ends of the wire overlapping; and an intersecting pin and slot connection provided by the overlapping ends to secure them with a relative freedom of movement in opposite directions along the plane of the loops.

JOHN H. DOMKEE.
